CLAIM

The ornamental design for an exercise bike as shown and described.

DESCRIPTION

FIG. 1 is a perspective view of an exercise bike showing embodiment 1 of my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown in the figures are for the purposes of illustrating portions of the exercise bike, which form no part of the claimed design.

1 Claim, 7 Drawing Sheets
